TARGET CONTROL DEVICE

Philip E. Davenport, San Leandro, Calif.

Application April 28, 1947, Serial No. 744,453

1 Claim. (Cl. 273—105.1)

1

This invention relates to an improved moving target control device and has particular reference to a novel moving target for use in the practice of shooting at mark, affording a most interesting and fascinating amusement and also providing an educational game for those desiring to improve their marksmanship.

The primary object of the present invention is to reflect a moving silhouette target through the medium of a revolving mirror having a silhouette provided thereon and the employing of a suitable light shining through a lens for directing a light beam on the said mirror, whereby the image of the silhouette is reflected on a wall, ceiling or screen and is shown in continuous motion as the mirror revolves.

A further object of the present invention is to secure the mirror having the silhouette thereon to a revolving shaft and to provide a spring member for retaining the mirror on the said shaft in a resilient manner, whereby the silhouette image is shown as wobbling and going through various irregular motions in its course of movement around the wall.

A still further object of the present invention is to revolve the said mirror through the medium of a conventional clock spring motor and to provide a manually operated means for stopping the motor.

A still further object of the present invention is to provide a moving target device of the character described that is durable, simple in construction, economical to manufacture and highly efficient and serviceable in use.

Other objects and advantages will be apparent during the course of the following description.

In the accompanying drawing forming a part of this specification, wherein for the purpose of illustration like numerals designate like parts throughout the same,

Fig. 1 is a perspective view of the device with certain portions of the housing broken away to illustrate some of the mechanism therein and also shows a person shooting at the reflected target, demonstrating the principle and novelty of the invention.

Fig. 2 is a side elevational view with the front wall of the housing removed to illustrate the clock spring motor, the gears and batteries within the housing.

Fig. 3 is a vertical sectional view taken on line 3 of Fig. 2, looking in direction of the arrow, and

Fig. 4 is a side elevational view of a flashlight gun employed in the invention and illustrates a method of making an electrical contact with the trigger for operating the flashlight.

Referring in detail to the drawings and to the numerals thereof, the numeral 1 designates as a whole a box-like housing having front and rear sides 8 and 9 respectively, opposite ends 10 and 60

2

11 and a bottom 12. The top 13 of the housing is preferably hingedly secured to one end thereof as at 14 and is substantially fastened to the opposite end by suitable hooks 15. The numeral 16 designates a cylindrical container extending upwardly at an angle from the horizontal wall 17, which wall is provided with an insulated projection 18 that is adapted to fit in the container and support the same. The light socket 19 is secured into the said projection in any suitable manner. The numeral 20 designates an electric light, which light can be a flashlight adapted to be used in conjunction with electric batteries or can be any suitable electric light operated from a regular line and connected thereto by an electric cord and plug or in any other conventional manner.

The present illustration shows the source of electric supply as consisting of a series of electric batteries 21, 22 and 23 supported on the horizontal wall 24 of the housing and retained in position by the partition 25 and end piece 26. Suitable electric conductor members 27, 28, 29, 30, 31 and 32 are shown to provide the means for connecting the series of batteries to the light socket 19, a suitable switch 33 controlling the circuit. The said switch 33 and conductors 28 and 29 are preferably secured to the cover 13. Any conventional method well known in the art can be employed for electrically connecting the said batteries to the light.

A suitable lens 34, preferably a magnifying lens, is positioned in front of the light 20 and fixed into the wall of the container 16 as shown to advantage in Fig. 3. A suitable mirror 35 preferably concave in shape, is also fixed to the wall of the container 16 and positioned at the rear of the light 20 and in alignment with the said light and lens, whereby a beam of light is directed on the mirror 36 as shown to advantage in Figs. 1 and 3. A cover 37 closes the container 16, thus confining the light to the lens. The mirror is preferably fixed on a suitable support or frame 38 which is recessed or split as at 38' for receiving an elongated thin flat member 39 that is fixed thereto by a suitable screw 40 or a plurality of screws sufficient for securing the parts together. The said elongated flat member 39 is preferably constructed of a thin spring metal for enabling the mirror to wobble during its rotation, but can be a rigid piece if desired and is adjustably mounted in a slotted shaft 41 and secured thereto by a set screw 42. The said shaft 41 is revolvably supported in the front housing wall 8 and the inner vertical wall 43.

The preferred means employed for imparting revolvable movement to the said shaft 41 and mirror 36 comprises a conventional clock spring motor 44 having a drive shaft 45, which drive shaft 45 is operatively connected to the said

mirror shaft 36 through the gears 46, 47 and 48 as shown to advantage in Fig. 3, the said gears being fixed on their respective shaft, the numeral 49 designating the shaft for the idler gear 47. The gears may be of any relative size for obtaining the desired revolving speed of the mirror. The clock spring motor 44 is of the conventional type well known in the art, which motors are constructed to operate at the desired speed. The said motor is secured to the bottom 12 of the housing by suitable bolts 50. A control pin 51 slidably mounted in the housing end wall 11 engages the motor drive shaft gear 46 as shown to advantage in Fig. 2 for stopping the motor and can be disengaged therewith for starting the same. The numeral 52 designates the key for winding the motor. The flashlight gun employed in conjunction with the moving target device herein described can be a standard type or the flashlight and mechanism can be provided on a toy gun or a regular gun. In the present illustration the numeral 53 designates the gun barrel, 54 the stock and 55 a conventional spring controlled metal trigger. The numeral 56 designates a suitable spot-type flashlight clamped to the gun barrel 53 by clamping bands 57. The numerals 58 and 59 designate plus and minus insulated electric conductors, respectively, leading from the flashlight to the rear of the trigger 55 and each of the said conductors 58 and 59 are provided at their outer extremities with metal contact members 59 and 60, respectively, that are fixed to the trigger guard and are insulated therefrom. When the trigger 55 is pulled the said members 59 and 60 are contacted, thus closing the circuit and lighting the spot flashlight. The said flashlight can be fixed on the outer extremity of the gun barrel or positioned in the gun barrel if desired.

The silhouette 61 is of any suitable material and can simulate an airplane, a deer or other animal, or a flock of fowl, etc. The said silhouette is positioned on the outer face of the mirror and is preferably removably secured thereon by a bolt and nut 62 and 63, respectively, whereby different silhouettes can readily be employed.

From the foregoing description taken in conjunction with the drawing illustrated in Fig. 1, it will be obvious that when the device is in operation a light beam 64 is directed on the mirror 36 and the image of the said mirror is reflected on the ceiling 65 or the wall 66, with the portion blocked out by the silhouette shown in black. The revolving of the mirror will cause the image of the silhouette to have a travelling movement. 55

When the housing is placed on its side the target image will travel horizontally around the walls instead of vertically across the ceiling and wall. If the mirror vibrates during its revolving movement the image of the silhouette will be caused to wobble during its travelling movement. If the player, designated by the numeral 67, aims at the moving target image and scores a hit, that portion of the target hit will be blocked out with light as shown at 68. Thus an educational and an exceptional fascinating target practice game has been produced.

It is to be understood that the form of my invention herewith shown and described is to be taken as a preferred example of the same and that various changes relative to the shape, size, material and arrangement of parts may be resorted to without departing from the spirit of the invention or the scope of the subjoined claim.

Having thus described my invention, I claim:

In combination with a wall, a target control device of the character described comprising a rectangular housing, a plurality of gears revolvably supported within the housing, a spring motor associated with the gears for revolving the same, an elongated flat spring keyed to one of the gears and horizontally extending beyond one of the vertical walls of the housing and capable of being revolvable therein when revolvable movement is imparted to the said gears, a substantially flat member fixed on the outer end portion of the said flat spring, a mirror positioned on the said flat member, means including a silhouette provided on the mirror and capable of directing a light beam on the same and the silhouette thereon, whereby a reflection of the target image is directed on the wall and is vibrated when the mirror supported on the said elongated flat spring is revolved.

PHILIP E. DAVENPORT.
